Specification for Design.

Patented Mar. 23, 1920.

Application filed May 31, 1919. Serial No. 301,090. Term of patent 14 years.

To all whom it may concern:

Be it known that I, ARTHUR J. ROWLAND, a citizen of the United States, residing at Shelburne Falls, county of Franklin, State of Massachusetts, have invented a new, original, and ornamental Design for a Handle for a Knife, Cleaver, or Similar Article, of which the following is a specification, reference being had to the accompanying drawing, forming a part thereof.

In the drawing; Figure 1 is a perspective view illustrating the invention as applied to a carving knife, a cleaver being indicated by dotted lines;

Fig. 2 an enlarged side elevation of the handle; and

Fig. 3 is a transverse section of the handle.

What I claim is—

The ornamental design for a handle for a knife, cleaver or similar article, substantially as shown.

In testimony whereof I affix my signature.

ARTHUR J. ROWLAND.
